UNITED STATES PATENT OFFICE.

KENT HALE SMITH, OF CLEVELAND, OHIO.

GRENADE.

1,344,733.

Specification of Letters Patent. Patented June 29, 1920.

Application filed December 3, 1917. Serial No. 205,028.

To all whom it may concern:

Be it known that I, KENT HALE SMITH, a citizen of the United States, and a resident of Cleveland, county of Cuyahoga, and State of Ohio, have invented a new and useful Improvement in Grenades, of which the following is a specification, the principle of my invention being herein explained and the best mode in which I have contemplated 10 applying that principle, so as to distinguish it from other inventions.

It is well known that serious accidents frequently occur in connection with the use of the small grenades or bombs which are 15 employed in large quantities in modern trench warfare. These grenades, which are principally thrown by hand, are designed to explode upon impact, and so if accidentally dropped, of course produce a disaster 20 in the midst of the attacking force. So serious is this menace that the order has recently been issued in a certain army that the man who thus accidentally drops such a hand grenade or bomb, shall immediately 25 fall on the same himself to smother the explosion, since his death is certain anyhow, and injury to his fellows may in this way be prevented.

The object of the present invention is to 30 provide a missile of the sort just described which may be handled with comparative impunity, that is, will be secure against accidental or premature explosion, but which will become fully operative, or capable of exploding on impact, following its discharge, 35 that is upon being thrown at the enemy.

To the accomplishment of the foregoing and related ends, said relation, then consists of the means hereinafter fully described 40 and particularly pointed out in the claims, the annexed drawing and the following description setting forth in detail certain mechanism embodying the invention, such disclosed means constituting, however, but 45 one of the various mechanical forms in which the principle of the invention may be used.

In said annexed drawing:—

Figure 1 is a central vertical section 50 through a grenade or bomb embodying my present improvements; Fig. 2 is a similar section, but showing certain parts in a different operative position; Fig. 3 is a transverse section of the detonating mechanism, 55 taken on the plane indicated by the line 3—3, Fig. 1; Fig. 4 is a cross-section through the

controlling device, the section of the plane being indicated by the line 4—4, Fig. 1; and Figs. 5 and 6 are modifications.

As usual in devices of the sort in hand, 60 the present improved hand grenade or bomb consists essentially of a hollow approximately spherical metal body 1, preferably made of castiron, within which the high explosive is packed. In the present device this 65 main body of the bomb is flattend on one side, such side 2 being threaded to receive a segmental cover 3 within which the controlling device, presently to be described, is located.

For setting off the explosive in the main body of the bomb, one or more detonators 4 are provided, these being carried in the cylindrical wall 5 of a plug 6 screw-threaded into an opening in the top of the body 1 so 70 as to project inwardly toward the flattened side 2 of the latter. For setting off the detonator, a flat spring 7 is attached to the inner face of the plug, which is inclosed by the aforesaid cylindrical wall, such spring carrying 75 a steel pin or head 8 that, upon vibration of the spring, will strike and set off one or both of the detonators 4. This necessary vibration of the spring is of course produced upon the bomb coming into contact with any 80 obstacle.

Extending inwardly from the flat side 2 of the body 1 is a tubular projection 9 within which the inner end of the cylindrical wall 5 on the plug 6 snugly fits, and threaded in 90 a suitable central opening in the flat side of the body, so as to lie co-axially with this projection and the plug, is a screw 10. At its inner end the latter carries a guard in the form of a cylindrical shell 11 that in one 95 position of the screw, as shown in Fig. 1, surrounds the head 8 on the detonating spring, while in another position of such screw this head is left unguarded, as shown in Fig. 2. The end of the screw that lies 100 within the chamber under the cover 3, in what may be called the bottom of the bomb, is provided with arms 12 heavily weighted at their outer ends, as by pieces 13 of lead, and the thread on the screw is carefully fitted to 105 that in the hole so as to allow the screw to rotate easily.

Normally such rotation is prevented by the use of a safety lock in the form of a pin 14 that projects through a hole in a cover 3 110 into engagement with an alined hole 15 in one of the weighted arms. Upon removal

of this pin, however, it will be obvious that by imparting a whirling motion to the bomb about a plane parallel with the flat side of the main body of the same in a direction opposite to that of the thread on the screw, the latter, owing to the inertia of the weighted arms on its lower end, will be rotated relatively to such flat side, or rather the latter will be rotated relatively to and around such screw, which tends to resist rotation, until the guard on its upper end uncovers the detonating pin. The screw may be formed with a projection 16 on its lower end adapted to engage a stop 17 on the cover when this point is reached, as shown in Fig. 2. It will also be noted that by screwing the plug 6 which carries the detonating device in or out, the amount of longitudinal travel of the screw necessary to uncover the detonating pin may be varied.

In order to insure that the bomb will be thrown in the proper manner, that is so that it will rotate about the axis of the screw 10, the exterior surface of the body and cover are formed with appropriately located impressions or grips 18 for the thumb and fingers of the user. Accordingly, assuming the base plug to have been properly located to cause the bomb to become alive at the desired distance, the user will simply withdraw the safety pin, seize the bomb in the fashion determined by the location of these impressions, and throw the bomb in the ordinary fashion as at present prescribed by army regulations. As the bomb is thrown, and travels through the air, a rotative movement will be imparted to it as a matter of course, and only after it has thus traveled a predetermined distance will the screw be withdrawn sufficiently to uncover the detonating pin. Then, upon encountering an obstacle, the bomb is immediately exploded. Before it is thus thrown, however, it can be dropped with comparative safety, since the detonating pin is of course guarded, as need not be further explained.

The modification in construction illustrated in Fig. 5 relates to the form of detonating device, the object being to make more sure and certain the explosion of the charge, no matter with what side the grenade or bomb strikes. It is conceivable, in other words, that, with the form of detonating device illustrated in Figs. 1 and 2, if the bomb struck on an axial line passing longitudinally through the spring 7, the latter might not be set in vibration with sufficient force to cause the head 8 to set off the detonators 4. In the modified construction, accordingly, two or more flat springs 20 are provided, being suitably held in a cylindrical chamber 21 on the inner face of the flat side 2. The ends of these springs nearest to such side are attached to a weighted ring 22 provided with striking points or needles 23

for setting off corresponding detonating caps 24 secured in the adjacent portion of the chamber wall, upon movement of such ring toward the side 2. Light compression springs 25 normally retain the ring in the position shown in Fig. 5.

The opposite ends of the spring 20 are pointed and disposed to set off detonating caps 26 whenever the springs are straightened out, which will be effected by the action of weights 27 attached to their intermediate portions whenever the bomb strikes on its end, so that it will be seen that however the bomb strikes, it is practically certain to be set off with this type of detonating device.

For rendering the device inoperative a guard operated in the same manner as that hereinbefore described is provided, such guard, however, taking the form of a solid cylindrical projection 28 instead of a shell 11 as in the previous construction. This projection normally projects between the weights 27 on the springs 25, and also carries a collar 29 that engages with the ring 22. Accordingly, until such projection is withdrawn, along with the collar, by the rotation of the screw 10, the detonating device cannot be set off.

In Fig. 6 is illustrated a modified form of mechanism for controlling the withdrawal of the guard, or, in other words, the rotation of the screw 10, whatever specific form the guard proper may take. Attached to the end of this screw and to a suitable plug 30 inserted in the cover 3 directly opposite such end, is a torsion spring 31 which, in the normal position of the parts, tends to rotate the screw to withdraw the guard. This spring may be employed either in supplement to the weighted arms 12 or independently thereof as desired. By rotating the plug the tension of the spring may obviously be varied so as to speed or retard its action, whether exclusively relied on or not to rotate the screw 10.

Normally rotation of the screw 10 under the action of spring 31 is prevented by a release key 32, the outer end of which projects into one of the finger grips 18. A lock 33 serves to hold this key in operative position, but is thrown out of action when the finger of the user coming in contact with the outer end of the key forces the latter inwardly, such lock being thereupon held out of the way by a spring 34. When the grenade in this condition leaves the hand the key is free to fly out, and screw 10 may then rotate either under the influence of inertia or the action of the spring 31, or both.

Other modes of applying the principle of my invention may be employed instead of the one explained, change being made as regards the mechanism herein disclosed, pro-

vided the means stated by any of the following claims or the equivalent of such stated means be employed.

I therefore particularly point out and 5 distinctly claim as my invention:

1. In a device of the character described, the combination of a hollow body adapted to contain a suitable explosive; detonating means including a vibratory pin; a guard 10 normally covering such pin; and means controlled through inertia, adapted to withdraw said guard.

2. In a device of the character described, the combination of a hollow body adapted 15 to contain a suitable explosive; detonating means including a vibratory pin; a guard normally covering such pin; means, controlled through inertia, adapted to withdraw said guard; and a lock for said last 20 named means.

3. In a device of the character described, the combination of a hollow body adapted to contain a suitable explosive; detonating means including a vibratory pin; a guard 25 normally covering such pin; and a screw connected to withdraw said guard, said screw being weighted so as to resist turning when said body is rotated about the axis of 30 said screw.

4. In a device of the character described, the combination of a hollow body adapted to contain a suitable explosive; detonating means including a vibratory pin; a guard 35 normally covering such pin; and a screw connected at one end to said guard so as to withdraw the same upon relative turning movement between said body and screw, said screw being provided with weighted arms at its other end so as to resist turning 40 when said body is rotated about the axis of said screw.

5. In a device of the character described, the combination of a hollow body adapted

to contain a suitable explosive; detonating means including a vibratory pin; a guard 45 normally covering such pin; a screw connected at one end of said guard so as to withdraw the same upon relative turning movement between said body and screw, said screw being provided with weighted arms 50 at its other end so as to resist turning when said body is rotated about the axis of said screw; and finger grips formed on the exterior of said body, whereby rotation about such axis is insured upon throwing same. 55

6. In a device of the character described, the combination of a hollow body adapted to contain a suitable explosive; detonating means including a vibratory pin; a guard 60 normally covering such pin; a screw connected at one end of said guard so as to withdraw the same upon relative turning movement between said body and screw, said screw being provided with weighted arms 65 at its other end so as to resist turning when said body is rotated about the axis of said screw; finger grips formed on the exterior of said body, whereby rotation about such axis is insured upon throwing same; and a removable lock for preventing relative 70 turning movement of said screw.

7. In a device of the character described, the combination of a hollow, approximately spherical body adapted to contain a suitable explosive, said body being flat on one 75 side; a cover for such side providing a chamber; a plug screw-threaded into said body at a point opposite such side and carrying a detonating device; a screw threaded in such flat side co-axially with said plug 80 and carrying a guard for said detonating device; and weighted arms on the end of said screw projecting within such chamber.

Signed by me, this 28th day of November, 1917.

KENT HALE SMITH.
